209-260

Draftsmen.

No. 733,986.

PATENTED JULY 21, 1903.

T. R. MARSDEN.

ATTACHMENT FOR PNEUMATIC FEEDING TRUNKS.

APPLICATION FILED MAR. 7, 1903.

NO MODEL.

3 SHEETS—SHEET 1.

For fire
cause it to
burn freely
fire grate over
each of four hearths
so keep your hearths
grate free of dirt
& congealed pieces
means to continually
turn said grate
to place opposite
side over four hearths

UNITED STATES PATENT OFFICE.

THOMAS RODGERSON MARSDEN, OF OLDHAM, ENGLAND.

ATTACHMENT FOR PNEUMATIC FEEDING-TRUNKS.

SPECIFICATION forming part of Letters Patent No. 733,986, dated July 21, 1903.

Application filed March 7, 1903. Serial No. 146,700. (No model.)

To all whom it may concern:

Be it known that I, THOMAS RODGERSON MARSDEN, manager in the employ of Platt Brothers & Company, Limited, machinists, of Oldham, a subject of the King of Great Britain and Ireland, and a resident of Bank View, Dernier, Oldham, in the county of Lancaster, England, have invented certain new and useful Improvements in Attachments for Pneumatic Feeding-Trunks, (for which I have made application for patent in Great Britain, No. 11,244, dated May 16, 1902,) of which the following is a specification.

My said invention has reference to improvements in and applicable to hopper bale-breakers, hopper-feeders, and to other machines or apparatus for feeding or preparing cotton and other textile fiber. In machines of the indicated class it is now the custom to employ a fan in connection with air tubes or pipes to facilitate the removal of dirt and assist the even distribution of fiber, the air-tubes being provided with perforated doors, grids, or reticulated surfaces, as is well understood. These grids are liable to become choked or to have their surfaces compacted with dirt and fiber, so that the action of the fan is impaired. In practice I find that the dirt and fiber gradually accumulate until the suction of the fan can no longer sustain the weight of the accumulation, whereupon the compacted mass of dirt and fiber falls back into the machine and becomes incorporated, so that the cotton in the hopper or the like is fouled. To prevent choking of the grid and the undue accumulation of dirt and fiber, various scraping devices have been proposed; but these are open to the objection that the dirt removed thereby must of necessity fall back among the fiber fed, and so pass on through the machine.

According to my invention I propose to employ a reversible or rotatable perforated door, grid, or surface which is intermittently or otherwise rotated, so that the faces of the grid or reticulated device are alternately directly opposed to the uprising dust and dirt and thereafter quickly reversed. Thus what was at one time the active or opposing face of the grid becomes the non-active or passive face, and vice versa. Under this arrangement dust and dirt are allowed to accumulate

upon the grid for a suitable length of time, whereupon the grid is rapidly reversed and its layer or coating of dust and dirt is turned face in to the air-suction pipe, the accumulated mass being rapidly withdrawn or sucked away from the grid by the fan. By these means the dust and dirt is wholly withdrawn and permanently removed from the machine at suitable intervals, while the regular reversal of the grid renders the action of the fan more uniform and certain.

In order that my invention may be fully understood and one form of mechanism by which I carry the same into practical effect clearly explained, I will now describe the invention in detail and with reference to the annexed three sheets of drawings.

In the said drawings, on Sheet 1, Figure 1 shows my improved reversible or revolving perforated door or grid with suitable actuating mechanism in connection with a portion of a hopper bale-breaker, the figure being broken in length for want of space. On Sheet 2, Fig. 2 is an end elevation of the actuating mechanism seen in Fig. 1 looking in the direction of the arrow marked 1. Figs. 3 and 4 are enlarged detail views. On Sheet 3, Fig. 5 is a plan view of the perforated door or grid and connected mechanism, while Figs. 6 and 7 are detail views.

Under my invention, as before explained, I arrange to reverse or rotate the perforated door or grid *a*. To this end I support the perforated door or grid or other reticulated surface on trunnions or on a shaft *a'*, sustained in suitable bearings. The grid or reticulated surface is disposed in any convenient position—say, for instance, at the foot of the fan-pipe *b*, as clearly shown in the drawings—and is rotated intermittently by a spur-pinion *c*. This spur-pinion *c* is loose upon the shaft *a'* and is compounded with or secured to a clutch-half *c'*, the pinion and clutch-half being movable endwise against the action of the spring *c*. The clutch-half *c'* normally gears with a clutch-half *d*, fixed on the shaft *a'*, as more clearly shown in Figs. 2 and 4, such clutch-half being formed with projections or arms *d'*. The function of these projections or arms *d'* will be hereinafter explained.

To actuate the pinion *c*, I employ a mov-

able rack *e*, which on its upward movement rotates the pinion in one direction, while on its downward movement the direction of rotation of the pinion is reversed. With the arrangement shown in the drawings on the upward movement of the rack *e* the pinion is rotated from right to left, causing the clutch-half *c'* to slip over the clutch-half *d*, the pinion moving endwise against the action of the spring *c²*, so that no movement of the shaft *a'* results. On the descent of the rack the direction of rotation of the pinion is changed, whereupon the clutch-halves interlock, and by reason of the clutch-half *d* being fixed upon the shaft *a'* said shaft *a'* is rotated and the perforated door or reticulated surface *a* reversed. To prevent any possibility of the clutch-half *d* turning with the half *c'* on the upward movement of the rack *e*, I fix a ratchet-wheel *f* at the other end of the revolving door-shaft *a'*, and with this ratchet-wheel *f* a pawl *f'* gears. By these means the shaft is effectually prevented from turning save in the one direction and upon the descent of the rack *e*. The rack *e* is guided by studs *g*, which engages slots *e'*, or is otherwise supported so as to be free to slide or move within limits, said rack being normally held down by the pull of a spiral spring *h*.

The raising of the rack *e* is effected in the following manner: Upon a short shaft *i*, supported in brackets *j j'*, I mount a worm-wheel *k*, provided with a projecting pin *k'*. This worm-wheel is driven by a worm *l*, mounted on the side shaft *m*, which is in turn driven by worm-gearing from the beater-shaft *n* or otherwise, as desired. During about one-half revolution of the worm-wheel *k* the pin *k'* bears in the notch or recess *e²* or otherwise engages the rack *e*, lifting the same upward during such partial revolution. With the continued revolution of such worm-wheel *k* the pin *k'* is carried clear of the notch or recess *e²* and allows the spring *h* to pull down the rack *e*. The upward movement of the rack turns the clutch-half *c* without causing same to engage the half *d*; but on the rack being pulled down the direction of rotation of the spur-pinion *c* is changed and the door or grid is rapidly reversed.

The action of the mechanism is briefly as follows: I will suppose the rack to be in its lowest position and the machine to be at work. As the worm-wheel *k* revolves the pin *k'* comes into contact with the notch or recess *e²* in the rack *e* and, engaging therewith, at once commences to raise the rack against the pull of the spring. Continued revolution of the worm-wheel further raises said rack, rotating the pinion *c* and its clutch-half *c'*, which, however, merely slips on the half *d*. Thus as the rack ascends the door or grid *a* remains stationary, the ratchet-pawl *f'* absolutely preventing any movement in the one direction. As soon, however, as the pin *k'* in its revolution moves clear of the rack the spring *h* pulls the same down

smartly, so that the teeth of said rack now operate to turn the pinion in the reverse direction. When this occurs, the clutch-halves *c' d* gear immediately and the door or grid is rapidly reversed. To prevent the door making more than a half-revolution, a stud or bolt *o*, secured to the head of the rack *e*, is caused to engage one or other of the projections or arms *d'*, secured to the clutch-half *d*. (See Fig. 3.) By these means the door is checked in its revolution and the desired position assured.

I may mount the revolving perforated door or grid upon a shaft a portion of which is half-round, as is shown in Figs. 1, 2, and 6, and I may provide the edges of the perforated door or grid with leather strips *q*, so as to make the junction as air-tight as possible. Such an application of leather strips *q* is shown in the various figures, and perhaps most clearly in Fig. 7.

The form of mechanism hereinbefore described not only allows for a dwell or period of quiescence in respect of each face of the perforated door or grid, but also provides for a rapid reversal from one face to the other.

This system in practice has given good results, and I have employed such gear to drive the worm-wheel *k* as to give a reversal about once every five minutes. This may, however, be obviously varied. The shock on rapid reversal, due to the pull of the spring on the release of the rack, I find to be beneficial in loosening the accumulation.

By means of my invention I am enabled to present at intervals a clean or fresh face to the mass of cotton and dirt, thereby vastly improving the action of the fan, while the dirty accumulated mass resting on the reversed face is quickly and permanently removed from the machine.

It will be obvious that the mechanism herein described is susceptible of some modification without at all departing from the spirit of my invention.

Any suitable arrangement of air tubes or pipes may be used in connection with my improved reversible or alternating grids, and a single fan may be employed for each grid and air-tube or for a number of such grids and tubes, as desired.

My invention is not restricted to hopper bale-breakers and hopper-feeders, but may with advantage be applied to rag-machines, so-called "dusting-machines," which are used for removing dirt from cotton and woolen waste, willows, and gins, and to other machines for dealing with textile fibers and in which dust-cages are not applicable.

In the drawings, A represents the side of the upper part of the hopper bale-breaker.

B is the ordinary beater, and C is the spiked lattice, only so much of known parts being shown as will facilitate a clear comprehension of my invention.

I declare that what I claim is—

1. In a device of the class described, the combination with a fan and an air-pipe of a reversible, perforated door for said pipe, substantially as described.
- 5 2. In a device of the class described, the combination with a fan and an air-pipe, of a reversible door for said pipe and means for operating the same, substantially as described.
- 10 3. In a device of the class described, the combination with a fan and an air-pipe, of a reversible perforated door and means for operating the same, substantially as described.
- 15 4. In a device of the class described, the combination with a fan and an air-pipe of a reversible perforated door for said pipe and means for intermittently operating said door, substantially as described.
5. In a device of the class described, the combination with a fan and an air-pipe of a reversible perforated door for said pipe and automatic means for operating the same, substantially as described.

In witness whereof I have hereunto set my hand in presence of two witnesses.

THOMAS RODGERSON MARDEN.
